United States Patent Office.

JOEL F. FALES, OF WALPOLE, MASSACHUSETTS.

Letters Patent No. 74,328, dated February 11, 1868.

IMPROVEMENT IN MACHINE FOR SEWING CARPET-LINING.

The Schedule referred to in these Letters Patent and making part of the same.

TO ALL WHOM IT MAY CONCERN:

Be it known that I, JOEL F. FALES, of Walpole, in the county of Norfolk, and State of Massachusetts, have invented new and useful Improvements on Carpet-Lining Machine; and I do hereby declare that the following is a full, clear, and exact description thereof, which will enable those skilled in the art to make and use the same, reference being had to the accompanying drawings, forming part of this specification, in which—

Figure 1 represents a side sectional view of a carpet-lining machine, with my improvements attached, taken in the line *y y*, fig. 2.

Figure 2 is a vertical cross-section, taken in the line *x x*, fig. 1.

Figures 3, 4, and 5 are details.

Similar letters of reference indicate corresponding parts.

This invention relates to improvements on a carpet-lining machine, for which a patent was granted to John R. Harrington, dated April 1, 1858, which improvements consist in the combination of the guide-rollers, the smoothing-plate, a sewing-mechanism, and the feed-rolls, said smoothing-plate and sewing-mechanism being arranged between the guide and feed-rolls, as will be hereinafter more fully described.

A is the frame, on which, as in the Harrington machine, are hung the small guide-rolls, *B B' B''*, which receive the sheet-paper from the feed-rolls, *D D'*, above and below, for the lining of the carpet, with the batting between them, as usual, and the large measuring-rolls, *C C'*, all arranged and operating, by gearing, in the usual way. On one end of one of the measuring-rolls, *C*, is affixed a wheel, *E*, having a tooth or spur, *a*, on its periphery, which engages in the teeth *b b'*, on a wheel, *F*, and on the side of the wheel *F* is a spur, *c*, that catches a hammer, *d*, which strikes a bell, and thus gives the signal when the measurement-rolls have made a certain number of revolutions, and passed between them a given number of yards of fabric, as shown in fig. 4 in detail. In front of the guide-roll *B* a frame, *G*, is placed, to support a set of sewing-machines for stitching or quilting the fabric as it moves forward to the measuring-rolls. The needles *e e'*, any desired number, are set in this frame above the fabric, and the looper *g*, for each needle, underneath, and to which motion is to be given by means of any suitable gear-connection with the driving-shaft *h*, and so speeded as to move in concert with the fabric passing between the measuring-rolls. Between the frame *G* and the guide-roll *B* is placed a flat metal smoothing-plate, *H*, which has a double-incline rib, *k k'*, running from the middle, on the rear side, to the ends of the plate, for the purpose of pressing out the wrinkles in the paper as it comes up to the sewing-needles, the wrinkles being carried to the edges successively. An adjusting set-screw, *m*, is arranged to bear on each end of the feed-rolls, *D D'*, hung on uprights, *n n'*, for the purpose of keeping the paper from passing beyond the ends of the roll, and producing friction.

Having thus described my invention, what I claim as new, and desire to secure by Letters Patent, is—

1. The combination of the guide-rolls *B B''*, smoothing-plate *H*, a sewing-mechanism, and feed-rolls *C C'*, all arranged and operating substantially as set forth.
2. The arrangement of the spring *u*, adjusting-screw *m*, and feed-roller *D'*, as herein described, for the purpose specified.
3. In combination with a carpet-lining machine, constructed as described, the sewing-device, smoothing-plate *H*, wheels *E F*, hammer *d*, spring *u*, and set-screw *m*, all arranged and operating as described, for the purpose specified.

JOEL F. FALES.
